Primary Examiner — Cynthia Ramirez(74) *Attorney, Agent, or Firm* — Shlesinger, Arkwright & Garvey LLP(57) **CLAIM**

The ornamental design for a necklace changeable to a pendant, as shown and described.

DESCRIPTION

FIG. 1 is a front perspective view of my necklace changeable to a pendant in its closed necklace position; and, FIG. 2 is a front perspective view of my necklace changeable to a pendant of FIG. 1 in its open pendant position. The unillustrated top, bottom, left, right, and rear views form no part of the claimed design. The phantom lines shown do not form a part of the claimed design.
